CLAIM

The ornamental design for a seedling protector, as shown.

DESCRIPTION

FIG. 1 is a top and front perspective view of a seedling protector showing my new design;

FIG. 2 is a top plan view thereof;

FIG. 3 is a bottom plan view thereof;

FIG. 4 is a front elevational view thereof; and

FIG. 5 is a rear elevational view thereof, the adjacent sides being substantially similar in appearance.

FIG 1

FIG 2

FIG 3

FIG 4

FIG 5
